UNITED STATES PATENT OFFICE.

GUSTAV EGLOFF AND JOSEPH G. ALTHER, OF CHICAGO, ILLINOIS, ASSIGNEES TO UNIVERSAL OIL PRODUCTS COMPANY, OF CHICAGO, ILLINOIS, A CORPORATION OF SOUTH DAKOTA.

APPARATUS FOR CRACKING HYDROCARBONS.

Application filed December 23, 1920, Serial No. 432,847. Renewed March 24, 1927.

This invention relates to an improvement in an apparatus for cracking hydrocarbons and refers more particularly to an apparatus in which the heat generated is economically used to heat the raw oil and the raw oil used to dephlegmate and condense the generated vapors.

Among the salient objects of the invention are to provide an apparatus, different portions of which are maintained under differential pressures and one in which subsequent to the cracking or releasing of the generated vapors, they are dephlegmated by being passed in close relation to the incoming raw oil and thereby fractionally condensed, to provide an apparatus in which the vapors, after being fractionally condensed, are finally condensed in a multi-whirl condenser in which the cool raw oil is circulated about the uncondensed vapors, taking up their heat and causing them to be liquefied into a distillate; to provide an apparatus whereby the heat of the residuum is transferred to a portion of the incoming raw oil by circulating the latter about tubes in which the residuum is contained, and to provide an apparatus in which regulated quantities of the raw oil and the reflux condensate are charged to the heating tubes for treatment.

The figure is a side elevation, partly in section, of the apparatus.

Referring in detail to the drawings—heating tubes 1 are mounted in a furnace 2, preferably heated by means of gas burner 3. At 4 is an expansion chamber connected to the cracking tubes by means of a line 5 in which is interposed the valve 6. At 7 is a reflux condenser of the multi-whirl type connected to the expansion chamber by the vapor line 8 controlled by a valve 9. A vapor line 10 from the top of the reflux condenser directs the uncondensed vapors to a condenser 11 similarly constructed on the multi-whirl principle, which is connected to a receiver 12 by means of the pipe 13. A raw oil pre-heater 14 adapted to preheat a portion of the raw oil by means of the hot residuum drawn from the expansion chamber through the line 15 controlled by a valve 16 is likewise built on the multi-whirl principle. In operating this apparatus, the raw oil is introduced from any convenient source (not shown) through the pump 17, charging pipe 18 controlled by a valve 19 to the multi-whirl

condenser 11. In this condenser the raw oil is circulated about a plurality of vertically arranged tubes 20 in which the uncondensed oil vapors travel. To direct the course of the raw oil in this condenser, a helical baffle 21 is positioned therein and causes the oil to flow upwardly in a spiral course about the vertical tubes. When it reaches the top of the condenser it has absorbed a substantial part of the heat of the vapors and in liquefying the same has been preheated. From the top of the condenser the raw oil passes through a line 22 to the top of the reflux condenser 7 where it circulates about the vertical tubes 23 arranged therein, subjecting the generated vapors to a fractional condensing action due to the fact that the raw oil is at a lower temperature than the vapors contained in the vertical tubes. In the reflux condenser 7 the course of the raw oil is identical to that in the condenser 11 except that the oil flows from the top to the bottom of the reflux condenser as contrasted with its opposed direction of flow in the condenser. On reaching the bottom of the reflux condenser, the preheated raw oil charge is drawn off through the pipe 24 controlled by a valve 25, which communicates with the reflux line 26 leading back to the cracking tubes 1. In this line is interposed a valve 27. After being heated to a cracking temperature in the heating tubes, the oil charge, comprising raw oil and whatever reflux is added from the reflux lines, passes over to the expansion chamber where it is vaporized under a substantial pressure of the generated vapor. The released vapors pass off through the vapor line 8, any condensate forming in the vapor line flowing with the reflux back to the heating tubes. The oil vapors, on the other hand, rise through the vertical tubes 23 in the reflux condenser and, after being cooled by the cooler raw oil circulated about the vertical tubes on the spiral baffle 28, pass off through the vapor line 10 to the condenser 11. There the vapors pass through the vertical tubes of the condenser with the raw oil circulating thereabout as a condensing medium, the final distillate produced in the condenser being directed to the receiver 12 through the connecting line 13. The receiver is equipped with the usual indicating devices, such as pressure gauge 29 and liquid level gauge 30, besides having a pressure relief pipe 31 con-

trolled by a valve 32 and liquid draw-off 33 regulated by a valve 34.

It is obvious, of course, that the raw oil and the vapors are kept out of contact in both the reflux condenser and the final condenser and the heat transfer taking place slowly through radiation. At both ends of the reflux condenser and the final condenser are enlarged chambers into which the vertical pipes lead.

Returning now to the apparatus for utilizing the heat from the residuum drawn off from the expansion chamber, a multi-whirl preheater or residuum cooler 14 of similar construction to both the reflux condenser and final condenser is connected to the residuum draw-off in the expansion chamber. By introducing raw oil from the same, or a like source, as that from which the raw oil through the pump 17 is obtained and charging it to the lower portion of the residuum cooler through a pump 35 and line 36 controlled by a valve 37 and causing it to circulate upward in a spiral course about the vertical tubes 38 in which the hot residuum is caused to flow, this portion of the raw oil absorbs considerable heat from the hot residuum. The preheated oil, after its forced circulation about the hot residual oil, is drawn off through the pipe 39 regulated by a valve 40 and introduced into the combination reflux and charging line 26 in regulated quantities.

In efficiently operating this apparatus, the heating coil may be maintained at a temperature of 850° F. and under a pressure of approximately 250 pounds or thereabouts. The temperature in the expansion chamber would approximate 745° F. while that in the reflux condenser would range from 700° F. to 400° F. and, after being introduced to the final condenser, the temperature would be reduced substantially lower than the end point of the distillate collected in the receiver. The raw oil being introduced at from 60-75° F., according to atmospheric conditions, is subjected to the temperatures previously mentioned in the condenser and reflux condenser and is charged into the heating coil with the reflux after receiving an additional quantity of preheated raw oil from the residuum cooler. The apparatus affords an oppor-

tunity for utilizing a greater amount of the heat generated in the cracking or heating zone, the greater part of which has heretofore been permitted to be dissipated into the atmosphere. Further, by use of circulating mediums, such as raw oil, about the condensing and refluxing stages of the apparatus, a more accurate regulation and a more direct control of the temperatures may be obtained.

We claim as our invention:—

1. In an apparatus for cracking hydrocarbon oils, the combination with a furnace, of a cracking coil therein, an expansion chamber adjacent said coil into which oil is delivered, a reflux condenser, means for passing generated vapors to said reflux condenser, means for feeding charging stock to the reflux condenser to condense the heavier insufficiently cracked vapors, means for discharging residual oil from said expansion chamber, a preheater receiving said oil, means for feeding an independent supply of charging stock to said preheater, and means for introducing the heated charging stock from the preheater and the reflux condensate and charging stock from the reflux condenser to said cracking coil.

2. In an apparatus for cracking hydrocarbon oil, the combination with a furnace, a cracking coil therein, an enlarged expansion chamber adjacent said coil, means for introducing heated oil to said chamber where a substantial portion of the oil vaporizes, a reflux condenser, means for discharging vapors from said expansion chamber to said reflux condenser, a final condenser in communication with the reflux condenser, means for feeding charging stock to the reflux condenser, means for returning condensate and preheated charging stock to the cracking coil, means for withdrawing residual oil from the expansion chamber, a preheater receiving said oil, separate means for feeding an independent supply of raw oil to said preheater, and means for admitting said independent supply of preheated raw oil to the cracking coil with the reflux condensate and charging stock passing from the reflux condenser.

GUSTAV EGLOFF.
JOSEPH G. ALTHER.
